AUTOMATIC TIMING DEVICE

Harold A. Wagner, Portland, Oreg.

Application July 28, 1941, Serial No. 404,305

7 Claims. (Cl. 192—139)

The present invention relates to automatic timing devices, and, while it is not necessarily to be limited thereto, it is particularly adaptable for timing the operation of a rotary machine.

With certain types of machines, such as concrete mixers, it is desirable to provide a timing device which will be automatically energized upon the loading of the machine and will prevent premature unloading thereof to insure a conformity of the product with certain standards. Such devices as have been proposed heretofore involve relatively complicated mechanisms of a delicate nature and are not only prohibitively costly but are unreliable in operation under severe conditions of service.

It is an object of the present invention to provide a new and improved timing device of the type described which comprises relatively few parts of simple design and of low cost manufacture.

It is a further object of the invention to provide a new and improved timing device which is particularly applicable for timing the operation of a rotary machine such as a concrete mixer, the device consisting of rugged parts capable of reliable performance under severe operating conditions.

It is a still further object of the invention to provide a new and improved timing device of the type described which is so constructed and arranged that the period of operation may readily be adjusted without requiring the use of any tools.

Further objects and advantages of the invention will appear from the following description, taken in connection with the accompanying drawings, while the features of novelty will be pointed out with greater particularity in the appended claims.

In the drawings, Figure 1 is a partial side view of a concrete mixer equipped with a timing device constructed in accordance with the present invention; Figure 2 is a front elevation of the timing device illustrated in Figure 1 with the cover thereof removed; Figures 3 and 4 are enlarged fragmentary views of the timing device illustrating the operation thereof; Figures 5 and 6 are cross sectional views of the timing device, taken along the lines 5—5 and 6—6, respectively, of Figure 2; and Figure 7 is an enlarged cross sectional view of a portion of the timing device, taken along the line 7—7 of Figure 2.

The timing device of the present invention will be described as it may be applied to a rotary machine such as a concrete mixer for de-

termining the period of operation thereof, though it will readily be understood as the description proceeds that the timing device may be adapted for use with other machines.

The concrete mixer, shown partially in Figure 1, may be of any suitable type comprising a rotatable drum 10, a feed trough 11, and a discharge spoon 12. Materials to be mixed may be fed into the drum 10 by means of a suitable skip 13 having rollers 14 cooperatively arranged on an inclined track 15 which track is supported at its upper end to an upright 16 of the mixer framework 17. As the skip 13 is moved upwardly along the inclined track 15 and to the drum charging position, the wheels 14 drop into the notches 18 provided in the tracks 15. The skip is then pivoted about the axis of the rollers 14 to a substantially upright position as shown by the dotted lines 13', to dump the material loaded therein into the feed trough 11 which will direct it into the drum 10. It will be understood that the drum 10 is in operation during the time of the loading thereof.

The discharging spoon 12, shown in the inoperative position, is connected through linkage 19 to an operating lever 21 suitably mounted on an extension 22 of the framework. By manipulation of the lever 21, the spoon 12 may be tilted downwardly to effect unloading of the mixed batch from the drum 10.

In order to prevent premature unloading of the drum, a timing device, indicated generally at 25, is provided and which is set into operation upon the charging of the drum simultaneously locking the discharge control lever 21 in the inoperative position, and maintaining it inoperative until the drum has made a requisite number of revolutions insuring a proper mixing of the batch therein. The timing device 25, mounted by means of suitable lugs 26 upon the mixer framework, includes a control bar 27 extending through the upper portion of the timer casing and mounted for longitudinal movement therein. In the released condition of the timer the control bar 27 is in the position illustrated in full line. The left end of the timer control bar 27 is connected by a link 28 to one arm 29 of a bell crank suitably pivoted as at 30 to the mixer frame member 16. A second arm 31 of the bell crank extends adjacent the skip track 15 and is adapted to be engaged by one of the skip rollers 14 as it drops into the notch 18 upon the unloading thereof into the mixer drum 10.

Upon engagement of the bell crank arm 31 by the skip roller 14, the bell crank is rotated in

the counterclockwise direction as viewed in Figure 1 and through link 28 the timer control bar 27 is moved thereby toward the right. Ex-bar 27 is moved from the right end of the timer control bar 24 is a rod 32 slidably arranged in a boss 33 and having an outer end adapted to be moved into a locking engagement with the control lever 21 upon movement of the control bar 27 to the right. Once the control bar 27 has been shifted to the set or locking position by a dumping of the skip, it is retained in such position by mechanism included in the timer 25, permitting a lowering of the skip 13 for the reloading thereof.

Depending downwardly from the timing device 25 is an operating arm 35 provided with a roller 36 on the end thereof and which is adapted to be cooperatively engaged by a cam 37 secured to the side of the drum 10. The cam 37 in engaging with the roller 36, once during each revolution of the drum, gives it a kick to the left and which movement is transmitted to the timer mechanism. After a predetermined number of revolutions of the mixer drum have been counted by the timing device, the control bar 27 is released for movement to the left, thereby unlocking the control lever 21 for the discharge spoon 12.

Referring now more particularly to Figure 2, which illustrates the timing device with the cover thereof removed, the device comprises a sheet metal casing 38 of a generally rectangular configuration. The control bar 27 is slidably mounted for movement in the longitudinal direction adjacent the upper wall of the casing 38, its movement being guided by suitable guide blocks 39 and 40 adjacent the opposite ends thereof. The control bar 27 is biased in the releasing direction, or to the left as viewed in Figure 2, by means of a spring 41, the left end of which may be anchored to the casing as at 42 while the right end is secured to a suitable point 43 on the bar 27. The bar 27 when moved to the set position, or to the right, is retained in such position by means of a latch 44 pivoted to the casing as at 45. The latch 44 is adapted cooperatively to engage with a lug 46 depending downwardly from the control bar 27, the latch 44 being biased upwardly or toward the control bar by means of a suitably arranged spring 47. The latch 44 is provided with a depending arm 48 which is adapted to be engaged by a notching means at the end of a predetermined period of operation of the mixer to effect the disengagement of latch 44 and to permit the control bar 27 to be moved to the left or to the releasing position under the force of spring 41.

The notching means comprises a longitudinal rack bar 49 slidably mounted upon the lower wall of the casing 38, its movement being guided in a direction substantially parallel with the control bar 27 by means including suitable guide blocks 51 and 52. The rack bar 49 is biased toward the left by means of a suitable spring 53, the left end of which is anchored to the timer casing and the right end to the rack bar 49. The rack bar 49 is provided with a plurality of teeth along its upper surface and which are adapted to be cooperatively engaged by a pawl 54 and a dog 55. The pawl 54 is adapted to be operated by the operating lever 35 depending from the timer for effecting a step by step or notching movement of the rack bar toward the right and into engagement with the latch arm 48. Referring more particularly to the view of Figure 5, the operating lever 35 is bifurcated at its upper end, a second strip portion 57 being se-

cured thereto and which extends in a generally parallel and spaced relation therewith. The operating lever is pivotally mounted on the timer casing by means of a pin 58 extending through the bifurcated end thereof, the outer end of the pin 58 being supported in a suitable bracket arm 59. The upper end of pawl 54 is pivotally mounted upon the transverse pin 61 extending between the upper ends of the operating lever, the lower end of the pawl being biased into engagement with the teeth of the rack bar 49 by suitable means such as a weight 62 provided thereon. The upper end of dog 55 is pivotally mounted on the pin 58 between the bifurcated ends of the operating lever, while the lower end thereof is biased into engagement with the teeth on the rack bar to hold it in the position to which it has been moved by operation of the pawl 54. The dog 55 is provided with an extension 63 opposite the tooth end thereof and which extension is adapted to be cooperatively engaged by a cam 64 provided on the control bar 27. The dog 55 is biased in the clockwise direction by means of a spring 65 connected between the extension 63 and the control bar 27 so that the tooth thereof is resiliently held in engagement with the teeth of the rack bar. The operating lever 35 of the timer is biased in the counterclockwise direction by means of a spring 66, one end of which is suitably anchored as at 67 to the operating lever below the pivot 58 thereof and the other end to a suitable point 68 on the casing whereby the roller 36 at the outer end of the lever is normally held in the path of the cam 37 on the mixer drum.

Referring now more particularly to Figure 3, the operation of the device thus far described is as follows. Upon engagement of the operating lever by the cam on the mixing drum the lever will be pivoted about the pin 58 in the clockwise direction, shifting the pawl 54 and hence the rack bar 49 to the right by a distance corresponding to the length of one tooth of the bar. During this movement of the pawl 54 the dog 55 will slide up out of the tooth slot in which it had been seated and drop into the next succeeding tooth slot. Upon the passage of the cam 37 past the roller 36 the operating lever will be restored to its normal position by the spring 66 and the pawl 54 will be shifted back, whereupon it will drop into the next tooth slot under the force of the biasing weight 62. Following a predetermined number of revolutions of the mixer drum, the right end of the rack bar 49 will be moved into engagement with the depending latch arm 48 and pivot it in the counterclockwise direction as indicated more clearly in Figure 4, in which position the latch 44 will be moved free of the lug 46 to permit the control bar 27 to move to the releasing position under the force of its biasing spring 41.

Upon movement of the control bar 27 to the releasing position, or to the left, the cam 64 will engage with the end of the extension 63 of dog 55 to pivot it in the counterclockwise direction about the pin 58. Movement of dog 55 in this direction will cause its tooth end to be lifted out of engagement with the rack bar 49 and into engagement with the under surface of the pawl 54, thereby shifting it also to the inoperative or disengaged position relative to the rack bar. The rack bar will then be freed to move to the reset position, or to the left, under the force of its biasing spring 53.

The operating period of the mixer is deter-

mined by the extent to which the rack bar 49 is permitted to return into a reset position away from the latch arm 48. In order to effect adjustment of the operating period, an adjustable stop 71 is provided for the rear end of the rack bar 49. As illustrated more clearly in Figure 7, the adjustable stop arrangement includes a tooth bar 73 arranged parallel with and adjacent the longitudinal line of travel of the rack bar 49 and defining a guideway therefor. The teeth on the bar 73 are preferably of the same pitch as the teeth on the rack bar 49. The adjustable stop 71 is provided with a plurality of teeth along one edge thereof for meshing cooperatively with the teeth on the bar 73 so that when it is dropped into position it is firmly held therein. The bar 73 may be calibrated in accordance with the number of teeth on the rack bar 49 and which will correspond with the range of revolutions to be made by the mixer drum. By moving the stop 71 to the left, the rack bar 49 will be permitted to move farther away from the latch arm 48 in the reset position and hence the length of travel which will be required thereof to effect engagement with the latch arm will be increased. Similarly, by moving the stop 71 to the right, the operating period for the mixer drum may be shortened. The stop 71 may be secured to the casing by a flexible lead such as a chain 74 and by means of which it may readily be lifted from one position and inserted in another. It will be obvious that no tools will be required for effecting such an adjustment and which can furthermore be performed in a minimum amount of time.

A suitable batch counter 75 may be provided in the casing of the timer for counting the number of successive batches of concrete mixed in the machine. As shown, the counter may be mounted for actuation by an extension of the latch arm 44 so that upon each releasing movement thereof the counter will be shifted one digit.

An audible indicator may also be provided in conjunction with the timing device in the form of a bell 76 which may be attached to the rear of the timer casing in any suitable manner. The hammer (not shown) for the bell 76 may be actuated by any suitable means such as lug 77 extending rearwardly through the slot 78 in the rear wall of the timer casing. Upon movement of the control bar to the left following release thereof, the lug 77 may engage with the bell hammer to give a signal to the machine operator indicating the completion of the operating cycle.

Upon movement of the control bar 27 to the releasing position, the lever 21 is unlocked, whereupon the discharge spoon 12 may be shifted thereby to the unloading position. Since operation of the lever 21 is precluded until release thereof by the timing device, a uniform mix of the concrete batch will be insured and the element of human error is eliminated from the operation of the machine.

The timing device as described involves relatively few working parts and which, furthermore, are of relatively simple design so that they may readily be made of rugged proportions so as to be capable of withstanding rough usage to which machines such as concrete mixers are accustomed to receive. The operation of concrete mixers inherently entails a dust laden ambient atmosphere, and such machines are, furthermore, usually left unprotected outdoors

in all types of weather. My timing device, however, will not become fouled by accumulations of dust, water or snow, and the casing need be merely tight enough to keep rocks and coarse sand out of the working mechanism. Ice will not substantially interfere with the operation of the device. Upon loading of the mixer, a force is imparted through the bell crank 29, 31 to move the control bar 27 to the set position, which is sufficiently great as will effect the breaking loose thereof from any ice encrustations. Similarly, the rack bar 49, having been reset at the completion of the last preceding cycle of operation of the machine, is in readiness for forward notching by means of the pawl 54. Since the driving pawl 54 is actuated through a relatively long lever arm, a frozen rack bar 49 will readily be broken loose from the casing. Once broken free, the rack bar will operate smoothly to the end of its stroke, after which it will immediately be returned to the reset position. The pawl 54 may be made from relatively wide and heavy stock so that it will possess sufficient strength for transmitting the required force between the operating lever and the rack bar.

While the timing device of the invention has been described in connection with a concrete mixer, it will be obvious to those skilled in the art that the device may readily be applied to other types of machines in which it is desired to lock a particular portion of the machine until a predetermined cycle of operation has been completed by another part thereof.

Having described the invention in what is considered to be a preferred embodiment thereof, it is desired that it be understood that the specific details shown are merely illustrative, and that the invention may be carried out by other means.

What I claim is:

1. A timer comprising a longitudinally movable control bar, means biasing said bar to a releasing position, said control bar being movable to a set position against the force of said biasing means, a pivoted latch for cooperatively engaging said control bar and retaining said bar in the set position, a longitudinally movable rack bar, said latch being mounted in said casing beyond one end of said bar, means biasing said rack bar away from said latch, notching means for engaging said rack bar and moving said one end of said rack bar into engagement with said latch for effecting the disengagement of said latch from said control bar, operating means for said notching means, means responsive to the release of said control bar for shifting said notching means to an inoperative position to permit resetting of the rack bar by the biasing means associated therewith.

2. A timer comprising a control member, means biasing said control member to a releasing position, said control member being movable to a set position against the force of said biasing means, a latch for engaging said control member for retaining said member in the set position, a rack bar, said latch being pivotally mounted in said casing beyond one end of said rack bar, means biasing said rack bar away from said latch, means for notching said rack bar into engagement with said latch and causing the disengagement of said latch from said control member, operating means for said notching means, and means on said control member for operative-

ly engaging said notching means upon the release of said control member for shifting said notching means to an inoperative position to permit resetting of said rack bar by the biasing means associated therewith.

3. A timer comprising a control member, means biasing said control member to a releasing position, means for moving said control member to a set position against the force of said biasing means, a latch for retaining said control member in the set position, a longitudinal rack bar, said latch being mounted in said casing beyond one end of said rack bar, means biasing said rack bar away from said latch, notching means for moving said one end of said rack bar toward said latch and into engagement therewith for effecting release of said control member, operating means for said notching means, means operatively associated with said notching means and adapted to be operated by said control member upon the release thereof to move said notching means to the inoperative position permitting resetting of said rack bar by the biasing means associated therewith, and adjustable stop means for limiting movement of said rack bar away from said latch.

4. A timer comprising a control member, means biasing said control member to a releasing position, said control member being adapted to be moved to a set position against the force of said biasing means, a pivoted latch for cooperatively engaging and retaining said control member in the set position, a longitudinal rack bar, said latch being mounted in said casing beyond one end of said rack bar, a pawl for cooperatively engaging said rack bar, means biasing said rack bar away from said latch, an operating lever for said pawl whereby said one end of said rack bar may be moved toward said latch and into engagement therewith for effecting release of said control member, a dog for cooperatively engaging said rack bar for preventing movement thereof away from said latch, means on said control member for shifting said dog and said pawl to the inoperative position upon the release of said control member, said rack bar being movable to the reset position by the biasing means associated therewith upon movement of said dog and said pawl to the inoperative position.

5. A timer comprising a casing, a longitudinally movable control bar mounted in said casing, a spring connected between said bar and said casing biasing said bar to a releasing position, said control bar being adapted for movement to a set position against the force of said biasing means, a latch for cooperatively engaging said control bar and retaining said bar in the set position, a longitudinal rack bar, said latch being pivotally mounted in said casing beyond one end of said rack bar, means biasing said rack bar

away from said latch, a pawl for cooperatively engaging said rack bar and notching said rack bar toward said latch and said one end of said rack bar into engagement therewith to effect release of said control bar, lever operating means pivotally connected to said pawl, a dog for engaging said rack bar and preventing reverse movement thereof, means on said control bar for operatively engaging said dog upon the release of said control bar and shifting said dog and said pawl to an inoperative position relative to said rack bar, said rack bar being movable to a reset position upon movement of said dog and said pawl to the inoperative position, and stop means for predetermining the reset position of said rack bar.

6. A timer comprising a casing, a longitudinally movable control bar mounted in said casing, means biasing said control bar to a releasing position, said control bar being adapted for movement to a set position against the force of said biasing means, a latch mounted on said casing and adapted to cooperatively engage said control bar and retain said control bar in the set position, a rack bar mounted for longitudinal sliding movement in said casing, means biasing said rack bar to a set position away from said latch means, notching means for shifting said rack bar step by step toward said latch means and into engagement therewith for effecting release of said control bar, lever operating means pivotally connected to said notching means, a cam on said control bar for operatively engaging said notching means upon the release of said control bar and effecting movement thereof to an inoperative position, said rack bar being movable to a reset position by the biasing means associated therewith upon movement of said notching means to the inoperative position, adjustable stop means for predetermining the movement of said rack bar in the resetting direction.

7. A timer comprising a casing, a control bar extending through said casing, means engaging one end of said bar for moving the other end thereof to a locking position, spring means biasing said bar to a releasing position, latch means for retaining said bar in the locking position, a rack bar slidably arranged in said casing, spring means biasing said rack bar away from said latch means, means for notching said rack bar into engagement with said latch, a cam projecting from said control bar for engaging and shifting said notching means to an inoperative position upon release thereof, a toothed bar defining a guideway for said rack bar, and a toothed stop block adjustably insertable into said guideway for limiting movement of said rack bar away from said latch.

HAROLD A. WAGNER.
